UNITED STATES PATENT OFFICE.

EDWARD WESTON, OF NEWARK, NEW JERSEY.

DESIGN FOR A CASE FOR ELECTRICAL MEASURING-INSTRUMENTS.

SPECIFICATION forming part of Design No. 21,445, dated April 5, 1892.

Application filed January 8, 1892. Serial No. 417,410. Term of patent 14 years.

To all whom it may concern:

Be it known that I, EDWARD WESTON, of Newark, Essex county, New Jersey, have invented a new and original Design for Cases 5 of Electrical Measuring-Instruments, of which the following is a specification.

My design consists in the novel configuration of the case of an electrical instrument, substantially as hereinafter described, and as 10 shown in the accompanying drawings.

In said drawings, Figure 1 is a face view of an instrument-case embodying my design, and Fig. 2 is a side view of said case.

Similar letters of reference indicate like 15 parts.

For purposes of convenience in description the case, as shown in the drawings, is considered to be in upright position. The upper portion of the periphery of the case at A is 20 curved in the form of a circular arc. The portions of the periphery B immediately adjacent to said part A are inclined inward. The portions C of the periphery immediately adjacent to the parts B are straight and par- 25 allel. The portion D of the periphery which extends between the parts C and at right angles to said parts is straight. At the angles E between the parts A and B and at the an-

gles F between the parts D and C the periphery of the case is rounded. Between the 30 parts B and C at G the periphery of the case is curved. The radius of curvature of the part G is greater than that of the rounded angles E and F. The front wall H of the case is flat. The depth of the case above the part 35 G, and measured from the front wall H to the rear wall I, is less than the depth of the case below the part G, measured from the front wall H to the rear wall J. This is clearly shown in Fig. 2. From the wall J to the wall 40 I extends a narrow wall K, Fig. 2, which is parallel to the lower wall D. At the meeting angles between the wall K and the walls C the periphery of the case is rounded, as shown at L, the radius of curvature at L being the 45 same as the radius of curvature at F. In the front wall H of the case may appear a curved opening M.

I claim—

The design for the case of an electrical 50 measuring-instrument, substantially as herein shown and described.

EDWARD WESTON.
